HIGH VOLTAGE GENERATOR

Nils E. Lindenblad, Port Jefferson, N. Y., assignor
to Radio Corporation of America, a corporation
of Delaware

Application February 10, 1937, Serial No. 124,983

14 Claims. (Cl. 171—329)

This invention relates to a method and means for generating extremely high potentials or voltages at high energy levels. This invention is a continuation in part of my copending application Serial No. 684,328, filed Aug. 9, 1933, a division of which Serial No. 4,475, filed Feb. 1, 1935, matured into Pat. #2,070,972, patented Feb. 16, 1937, to which a second fixed element is added to reduce corona discharge when the generating system is employed for producing extremely high potentials.

This application is specifically directed to a further improvement of a rotor system wherein an induction principle is combined with centrifugal force. The rotor system has a corona shield interposed between the fixed and movable elements to reduce corona.

The second fixed element is in the form of a split corona shield interposed between the fixed and rotating element to reduce corona effects when the generator is operated at extremely high voltages.

In one way of carrying out my invention for the generation of high direct current voltages, I charge metallic units, preferably particles of metal, by actual conductive contact with a direct current source. Then, by moving the particles away from the source, the voltages of the charges thereon are increased, in a manner which will be explained more fully hereinafter, and the charges can then be ultimately deposited upon a low voltage gradient-section of a charge-storing device or container.

In another arrangement, for producing high voltages according to my present invention, an induction electrode, either grounded, or preferably maintained at a high voltage, is insulatingly separated from a chargeable medium which may be a solid, a liquid or a gas, and, by the use of a point discharge electrode system connected to a direct current source, or preferably to ground. Ionization or corona is caused to take place through and/or about the chargeable medium. The charged medium is then moved or carried to a lower gradient area on a chargeable element, the high voltage surface of which is brought up to an exceedingly high voltage by the continued deposits from the charged medium.

A further and more specific object of my present invention is to provide systems which utilize my improved contact and induction principles for charging solid mediums such as belts and discs, for charging liquids such as oil and oil-containing metallic particles in suspension, and for charging gases.

The invention will best be understood by referring to the accompanying drawing, in which:

Fig. 1 is a perspective view partly in section of a disc system;

Fig. 2 is a perspective view partly in section of a disc system, similar to Fig. 1, except that the lower disc is of insulating material.

Referring now in detail to Fig. 1, a metallic cylindrical tube 1 is grounded through a conductor 2, which conductor may be in the alternative, if desired, connected to a relatively high source of potential. A mixture 3 of metallic powder and some insulating material, such as bronze powder and oil, is caused to fall to the surface of the rotating disc 4. The metallic particles are charged up and driven out by centrifugal force to the outer metallic plate or annular collector 5. Disc 4 is rapidly rotated by a shaft 6. However, this shaft is insulatedly supported upon the motor shaft 7 by insulation block 8, so that the source of potential may be impressed upon the shaft by brush 9, which potential then manifests itself upon metallic disc 4. Centrifugal force will therefore drive the oil and metal powder mixture horizontally between the rotating disc 4 and the stationary disc 10, into the interior of the shell 5, having an outlet 12 through which the oil may fall into a suitable piping system 13 for passage again into pipe 1. The oil and metallic mixture becoming charged up by the conductor will, in turn, deposit its charge on the interior surface of the shell 5, as a result of which higher voltages may be generated in this system, as compared with the arrangement shown in my earlier applications, and as a result thereof, there will be a tendency for a corona discharge to be built up. To overcome the disastrous effects which may result from the corona, a second metallic element is interposed between the fixed and rotating elements. This added element is in the form of two metallic rings 14 and 15, which are insulatedly supported by member 5 and insulated therefrom by insulating rings 16 and 17. The rings 14 and 15 may be electrically connected to the stationary disc 10 by metallic strips 11, or any other suitable means, if desired, may be connected to the rotating discs 4 or 10 by suitable brushes (not shown).

In the arrangement shown in Fig. 2, the lower disc 20 is provided with an upper surface 21 of insulating material. The oil from pipe 1 is preferably in this case pure oil. High voltages impressed upon shaft 6 through brush 9 will cause corona discharge at points 22 carried by the upper metallic plate 10. The insulating material 21,

however, will prevent short-circuiting of the corona discharge to the metallic plate 26. In this way, still higher charges for the annular collector 5 may be obtained. The system shown in Fig. 2, therefore, utilizes for charging the liquid medium an induction principle.

Various other changes will readily suggest themselves to those skilled in the art in carrying out the principles of my present invention. Therefore, my present invention is not to be considered limited by the various illustrations which are given merely as specific examples, but is to be given the full scope indicated in the appended claims.

15. What is claimed is:

1. A high voltage generator comprising a relatively fixed surface and a movable surface, a metallic corona shield surrounding said fixed and movable surfaces, means for feeding a liquid to said movable surface, means for charging said liquid, and means for discharging said liquid after being thrown out from said movable surface by centrifugal force.

2. A high voltage generator comprising a relatively fixed surface and a movable surface, a corona shield surrounding said fixed and movable surfaces, a metallic ring surrounding said fixed and movable surfaces and said corona shield, means for feeding a liquid containing metallic powder on said movable surface, means for charging said liquid, and means including said metallic ring for discharging said liquid after being thrown out from said movable surface by centrifugal force.

3. A high voltage generator comprising a fixed surface and a movable, metallized disc-like surface, a metallic member surrounding said fixed and movable surfaces forming a corona shield, means for feeding a liquid on said movable surface, means for charging said liquid, and means for discharging said liquid after being thrown out from said movable surface by centrifugal force.

4. A high voltage generator comprising a fixed surface and a pair of movable discs, one of said discs being of insulating material and the other disc being of conducting material and fastened to an insulating hub located on a rotatable shaft for moving said discs, a corona shield comprising a pair of metallic rings surrounding said discs, another ring member outside said pair of metallic rings, means for feeding a liquid on the surface of said movable disc, means for charging said liquid, and means for discharging said liquid after being thrown out from said disc by centrifugal force.

5. A high voltage generator comprising a fixed and a movable disc, said movable disc being formed of two parts, one part being of conductive material and the other of insulating material, the portion of said disc which is of conducting material being fastened to an insulating hub located on a rotatable shaft for moving said disc, a plurality of rings surrounding the periphery of said discs, and means for feeding liquid containing metallic particles between said discs by centrifugal force so as to impinge the inner surface of one of said rings.

6. A high voltage generator comprising a relatively fixed surface and a movable surface, a ring surrounding the periphery of said movable surface, a second ring interposed between the periphery of said movable surface and said first mentioned ring to act as a corona shield, means for feeding a liquid on said movable surface,

means for charging said liquid, and means for discharging said liquid after being thrown out from said movable surface by centrifugal force.

7. A high voltage generator comprising a relatively fixed surface and a movable surface, a ring surrounding the periphery of said movable surface, a second ring insulatedly supported by said first mentioned ring and interposed between the periphery of said movable surface and said first mentioned ring to act as a corona shield, means for feeding a liquid on said movable surface, means for charging said liquid, and means for discharging said liquid after being thrown out from said movable surface by centrifugal force.

8. A high voltage generator comprising a relatively fixed surface and a movable surface, a ring surrounding the periphery of said movable surface, a pair of rings interposed between the periphery of said movable surface and said first mentioned ring to act as a corona shield, means for feeding a liquid on said movable surface, means for charging said liquid, and means including said first mentioned ring for discharging said liquid after being thrown out from said movable surface by centrifugal force.

9. A high voltage generator comprising a fixed and a movable surface, a corona shield surrounding the periphery of said movable surface, a metallic ring surrounding said corona shield, means for feeding a liquid on said movable surface, means for charging said liquid, and means for discharging said liquid after being thrown out from said movable surface by centrifugal force.

10. A high voltage generator comprising a relatively fixed metallic surface and a movable insulating surface, a corona shield surrounding the periphery of said movable insulating surface, a metallic ring surrounding said corona shield, means for feeding a liquid on said movable surface, means for charging said liquid, and means including said metallic ring for discharging said liquid after being thrown out from said movable surface by centrifugal force.

11. A high voltage generator comprising a relatively fixed surface and a movable surface, a metallic corona shield surrounding said fixed and movable surfaces and electrically connected to said fixed surface, means for feeding a liquid to said movable surface, means for charging said liquid, and means for discharging said liquid after being thrown out from said movable surface by centrifugal force.

12. A high voltage generator comprising a relatively fixed surface and a movable surface, a metallic corona shield surrounding said fixed and movable surfaces and connected to said movable surface, means for feeding a liquid to said movable surface, means for charging said liquid, and means for discharging said liquid after being thrown out from said movable surface by centrifugal force.

13. A high voltage generator comprising a relatively fixed surface and a movable surface, a metallic corona shield surrounding said fixed and movable surfaces and connected to ground, means for feeding a liquid to said movable surface, means for charging said liquid, and means for discharging said liquid after being thrown out from said movable surface by centrifugal force.

14. A high voltage generator comprising a fixed and a movable surface, said movable surface being divided into two parts, one part being of conductive material and other part of insulating material, the portion of said movable surface which

is of conducting material being fastened to an insulating hub located on a rotatable shaft for moving said surface, said fixed surface having a plurality of discharge points facing the insulating part of said movable surface, a corona shield surrounding the periphery of said movable surface,

a metallic ring surrounding said corona shield, means for feeding a liquid on said movable surface, means for charging said liquid, and means for discharging said liquid after being thrown out from said movable surface by centrifugal force. 5
